his Attorney.

UNITED STATES PATENT OFFICE.

RICHARD COOPE HARVEY, OF LETHBRIDGE, ALBERTA, CANADA.

MACHINE FOR DOCKING LAMBS' TAILS.

1,399,479.

Specification of Letters Patent.

Patented Dec. 6, 1921.

Application filed July 8, 1920. Serial No. 394,791.

To all whom it may concern:

Be it known that I, RICHARD COOPE HARVEY, a subject of the King of Great Britain, residing at Lethbridge, Province of Alberta, 5 Dominion of Canada, have invented certain new and useful Improvements in Machines for Docking Lambs' Tails, of which the following is a specification.

My invention relates to a new and improved machine for docking lambs' tails, and the object is to provide a machine that will perform the work intended more easily than has been able to be performed heretofore, by an easy and humane method without undue loss of blood by the lamb. 15

I attain these objects by the mechanism illustrated in the accompanying drawings, in which:—

Figure 1 is a side elevation of the entire machine open ready for use;

Fig. 2 is a bottom plan view of the device;

Fig. 3 is a transverse vertical section on line 3—3 of Fig. 1.

The machine preferably consists of a guard-plate 1 secured to the top of a standard 2 bolted to a suitable support 3. Secured to the top side of the guard plate is a blade 4, and pivoted as at 5 to the outer end 25 of the guard-plate 1 is a lever 6, which is in the form of a blade as at 7 directly above the blade 4 and adapted to coöperate therewith when the lever 6 is lowered.

Fulcrumed to the standard 2 below the guard-plate 1 is a lever 8, having secured to one of its free ends a metal plate or plunger 9, preferably made of copper or other heat-retaining element. This plunger is adapted to extend vertically through an opening 10 in the guard-plate 1 just beneath the blade 4. As the lever 6 is lowered to sever the tail of the lamb, a vertically-arranged spring-actuated actuating rod 11 is forced downwardly, its lower end being connected as at 12 to the opposite end of the fulcrum lever 8, this action causing the plunger or singer 9 to move vertically upwardly, and is thus brought into contact with the lamb's tail at the point where it is docked. 45

It is desirable to keep this plunger or

singer 9 under heat to effect the proper singeing of the freshly cut end of the lamb's tail, and to effect this a torch or other heating element 13 is applied to the lower end thereof to maintain this plunger under a 55 certain heat, the effect of the heater plunger being, as stated, to singe or close the blood-vessel of the freshly severed member.

In operation, the lever 6, together with the blade 7, assumes a position relative to the blade 4 (as disclosed in Fig. 1) to receive the lamb's tail to be docked, whereupon the lever 6 is lowered, thus severing the tail and simultaneously actuating the heated plunger or singer 9, which, owing to the construction of the mechanism moves upwardly to singe the freshly severed portion to produce a more or less healing effect on the wound.

I claim:

1. A tail docking device comprising a support, a blade affixed thereto, a lever pivoted to said support and provided with a sharpened surface to coöperate with the fixed blade of the support, and a heated singer movable with respect to said support and arranged adjacent to said cutting edges adapted to singe the part being severed. 70

2. A tail docking device comprising a support, a guard extending laterally thereof, a fixed blade secured to said guard, a lever pivoted at one end to said guard and provided with a sharpened surface adapted to coöperate with said fixed blade, a heated vertically movable singer mounted upon said support and arranged adjacent to said fixed blade, adapted to singe the part being severed. 80

3. A tail docking device comprising a support, a guard adapted to extend laterally therefrom in either direction, a fixed blade carried at the outer end thereof, a lever pivoted adjacent to said blade at the outer end of said guard and provided with a sharpened surface which is adapted to coöperate with said fixed blade, a fulcrum lever mounted on said support below said guard carrying at one end a vertically movable singer which is mounted upon said support, arranged adjacent to said fixed blade, 90

95

100

and a spring-pressed actuating rod carried at the opposite end of said guard and attached to the other end of said fulcrum lever adapted to be actuated by the downward movement of the first-mentioned pivoted lever, whereby the singer is caused to move vertically upon the downward movement of

said first-mentioned pivotal lever to effect a singeing of the part being severed, and a heating element arranged adjacent to said singer for maintaining a given heat thereto.

In testimony whereof I affix my signature.

RICHARD COOPE HARVEY.
